UNITED STATES PATENT OFFICE.

CARROL A. CORBETT, OF GRAND RAPIDS, MICHIGAN.

ADVERTISING DEVICE.

1,251,755.

Specification of Letters Patent. Patented Jan. 1, 1918.

Application filed June 20, 1917. Serial No. 175,922.

To all whom it may concern:

Be it known that I, CARROL A. CORBETT, a citizen of the United States, residing at Grand Rapids, in the county of Kent and State of Michigan, have invented certain new and useful Improvements in Advertising Devices; and I do declare the following to be a full, clear, and exact description of the invention, such as will enable others skilled in the art to which it appertains to make and use the same.

My invention relates to improvements in advertising devices and more particularly to one which is so constructed as to form a closure for the coal holes commonly used in side walks and the like for dumping coal into basements below, means being provided for illuminating the device at night so that the advertising matter thereon will be conspicuously displayed.

The object of the invention is to provide a device of the class described which may be easily and inexpensively manufactured and marketed, yet one which will be highly efficient and durable and will interfere in no manner with dumping coal through the coal hole after the device has been removed.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a top plan view of the device in use;

Fig. 2 is a vertical section on the plane indicated by the line 2—2 of Fig. 1;

Fig. 3 is a view similar to Fig. 2, but showing the device removed from the coal hole;

Fig. 4 is an enlarged detail vertical section of a portion of the device; and

Fig. 5 is a detail bottom plan view showing more particularly the detachable connection between the supporting ring and the reflector.

In the drawings above briefly described, the numeral 1 designates a portion of a sidewalk or the like having a coal hole 2 equipped with the usual circular frame 3, the space circumscribed by said frame being usually closed by the common type of cover, whereas in the present invention, it is closed by the device itself. This device includes a

supporting ring 4 having a horizontally extending annular flange 5 resting on the frame 3, the body portion of said ring being received in said frame. An internal annular rib 6 is formed on the ring 4 between the upper and lower edges thereof, said rib supporting thereon a suitable lens or other appropriate transparent plate 7, a gasket 8 being by preference interposed between the two as shown. Any preferred means could well be employed for securing the transparent opaque plate 7 in place, but cement is preferably run in between the edge of said plate and the inner side of the ring 70 as indicated at 9. By this provision, it is insured that no water shall leak through the device.

A plurality of headed studs 10, preferably in the form of screws, depend from the lower side of the rib 6 and coact with keyhole slots 11, in securing a substantially parabolic reflector 12 in place, said slots being formed in a horizontal annular flange 12' positioned at the open upper end of the reflector as shown clearly in the drawings. By this connection, it will be obvious that the reflector may be easily attached and detached so that the electric bulb 14 within the reflector may be renewed whenever required.

The lamp 14 is carried in any appropriate type of socket 15 which is mounted at the inner end of the reflector 12, said socket having a detachable connection with a pair of current conducting wires 17, by means of a common type of plug 16. The two wires 17 are by preference twisted together in the usual manner and extend beneath the side walk or the like 1 to any preferred source of current, said wires being of sufficient length to permit the entire device to be removed from the frame 3 before said wires are detached, it being then a simple operation to disconnect said wires so that they may hang loosely and interfere in no manner with the dumping of coal through the coal hole.

When the device is removed, it is by preference inverted as will be clear from Fig. 3, and in order to prevent possible injury of the plate 7, lugs 19 are preferably formed on the upper side of the ring 4, so that said lugs will prevent the plate in question from coming in contact with the pavement. Although this means is preferred, on account of its simplicity, it will be obvious that any other appropriate details could well be em-

ployed for obtaining the same results, the invention being dependent in no manner upon such minor features of construction.

It is intended that the lower surface of the plate 7 shall carry advertising matter, and this matter may either be painted upon said plate or carried by a somewhat transparent sheet which will be secured to the plate. In either case, when the bulb 14 is 10 illuminated at night, the rays of light therefrom will be reflected upwardly through the advertising matter so that the same will be conspicuously displayed.

From the foregoing, taken in connection 15 with the accompanying drawing, it will be obvious that although my invention is of extremely simple and inexpensive construction, it will be a highly efficient device for the purpose intended. Since probably the 20 best results are obtained from the specific construction shown and described, such construction constitutes the preferred form of the device. I wish it understood, however,

that within the scope of the invention as claimed numerous minor changes may well 25 be made.

I claim:

An advertising device comprising a ring positioned removably in a side walk coal hole and carrying a panel permeable to light, a substantially parabolic reflector below said ring and having an outstanding flange on its edge, said flange contacting with said ring and having keyhole slots, headed studs depending from said ring and received removably in said slots to support said reflector, an electric light socket carried by said reflector, and flexible current conducting wires below the side walk and having a plug detachably engaged with said socket. 30 35 40

In testimony whereof I have hereunto set my hand in the presence of a subscribing witness.

CARROL A. CORBETT.
